UNITED STATES PATENT OFFICE

168,535

MACHINE SHOP TRAILER

Kibbey W. Couse, Newark, N. J.

Application March 7, 1952, Serial No. 18,822

Term of patent 14 years

(Cl. D14—3)

To all whom it may concern:

Be it known that I, Kibbey W. Couse, a citizen of the United States of America and a resident of Newark, in the county of Essex and State of New Jersey, have invented a new, original, and ornamental Design for a Machine Shop Trailer, of which the following is a specification, reference being had to the accompanying drawing, forming a part thereof.

Figure 1 is a side elevational view of a machine shop trailer showing my new design, the opposite side elevation being the same;

Figure 2 is a top plan view thereof;

Figure 3 is a side elevational view of the machine shop trailer, showing portions in open position and other portions in unfolded or extended position;

Figure 4 is an elevational view of the side of the machine shop trailer opposite that shown in Figure 3;

Figure 5 is a top plan view of the machine shop trailer as illustrated in Figure 3;

Figure 6 is a front elevational view of the machine shop trailer as illustrated in Figure 1;

Figure 7 is an end elevational view of the machine shop trailer as illustrated in Figure 3;

Figure 8 is a rear end elevational view of the machine shop trailer as illustrated in Figure 1; and

Figure 9 is a rear end elevational view of the machine shop trailer as illustrated in Figure 4.

I claim:

The ornamental design for a machine shop trailer, as shown.

KIBBEY W. COUSE.
